FIG. 1.

FIG. 2.

FIG. 3.

Inventor

J.P. Acord

By *William J. Acord*

Attorney

UNITED STATES PATENT OFFICE.

JOHN P. ACORD, OF MONTCOAL, WEST VIRGINIA.

WRENCH.

Application filed August 29, 1922. Serial No. 585,105.

To all whom it may concern:

Be it known that I, JOHN P. ACORD, a citizen of the United States, residing at Montcoal, in the county of Raleigh and State 5 of West Virginia, have invented certain new and useful Improvements in Wrenches, of which the following is a specification.

My invention relates to a new and useful improvement in sliding jaw wrenches, 10 adapted for use as either a pipe or nut wrench; and has for its primary object to provide an exceedingly simple, cheap, and effective device of this description, the movable jaw of which may be adjusted to any 15 desired point and there held by the grasp of the handle of the device.

A further object of my invention is to provide a wrench of the above indicated character, which can be easily and quickly 20 adjusted for engagement with a nut or pipe, and avoid the use of strength to bring about the adjustment of the sliding movable jaws, and to make the wrench out of three pieces of metal only.

25 These and like objects of my invention will be better understood as the description proceeds and as is specifically pointed out in the appended claim.

Referring to the accompanying drawing 30 which forms a part of this specification and which clearly illustrates the construction and operation of my invention,

Figure 1 is a side elevation of a wrench made in accordance with my improvement, 35 Fig. 2 is a section on line 2--2 of Fig. 1, and

Fig. 3 is a top plan view of the wrench.

In carrying out my invention as here embodied, 1 represents a stationary jaw, formed 40 with or secured upon a shank 2, which latter is preferably rectangular in section and has ratchet teeth 3 formed upon the one longitudinal edge thereof. A movable jaw 4 is formed upon the inner end of a shank 45 5. The shank 5 of the movable jaw is preferably rectangular in cross section and has ratchet teeth 6 formed on the one edge of same.

Each of the shanks 2 and 5 is provided 50 with a handle 7.

A sleeve 8 which is also rectangular in cross section to conform to the shape of the shanks 2 and 5 is pivotally connected as at 9 to the shank 5 of the movable jaw.

55 From the foregoing description of my invention taken in connection with the ac-

companying drawing, it can be readily seen that when a pipe or such is placed in position between the serrated edges 10 of the stationary and movable jaws, and the handles 7 are pressed together that the ratchet teeth 3 of the stationary jaw and the ratchet teeth 6 of the movable jaw will be brought into engagement with each other and the tighter the stress is upon the nut or pipe, the 60 tighter the stress will be on the handles 7 thus causing the ratchet teeth to firmly engage and lock with each other. It will be observed that upon grasping the tool handle 7 the shank 2 will tend to sever from the 70 part 4. This is eliminated due to the inclined end of the sleeve engaging the member 2 and holding the same against lateral movement. Thus a positive engagement of 75 the two serrated jaws is had.

In view of the foregoing description of my invention taken in connection with the accompanying drawing, it is thought that any further explanation as to the construction, operation and objects of same are unnecessary.

While I have shown and described the preferred form of my invention, I realize that various minor changes may be resorted to, without departing from the spirit and scope of the invention as claimed, therefore, I do not wish to limit myself to the exact details of construction shown, nor to the combination and arrangement of parts.

What I claim as new and desire to secure 90 by Letters Patent is:—

A wrench of the class described comprising a pair of parallel shank members having their adjacent opposed edges serrated and adapted for engagement one with the other, a handle formed on the one end of each of said shank members, an inverted U-shaped sleeve pivotally secured adjacent the ends of the arms thereof to one of said shank members and encircling the other of said shank members, the crown portion of said inverted U-shaped sleeve being inclined forwardly and slightly spaced from the outer edge of the last mentioned shank member 95 to permit of clearance and movement of said last mentioned shank member within said sleeve, and serrated jaws formed on the ends of said shank members opposite the handles, the jaw on-one of said shank members being angular in design.

In testimony whereof I affix my signature.
JOHN P. ACORD.
